US0D1017474S

(12) **United States Design Patent** (10) **Patent No.:** **US D1,017,474 S**
(45) **Date of Patent:** **** Mar. 12, 2024**

(54) **TRICYCLE**

(71) Applicant: **Katayama Kogyo Co., Ltd.**, Ibara (JP)

(72) Inventor: **Yota Kakuda**, Tokyo (JP)

(73) Assignee: **Katayama Kogyo Co., Ltd.**, Ibara (JP)

(**) Term: **15 Years**

(21) Appl. No.: **29/745,488**

(22) Filed: **Aug. 6, 2020**

(30) **Foreign Application Priority Data**

Feb. 9, 2020 (JP) 2020-002438

(51) **LOC (14) Cl.** **12-11**

(52) **U.S. Cl.**

USPC **D12/112**

(58) **Field of Classification Search**

USPC D12/107, 110, 111, 112, 114, 117

CPC B60K 1/00; B62J 1/00; B62K 3/00; B62K
